UNITED STATES PATENT OFFICE.

ANNIE BERLIN, OF BUFFALO, NEW YORK.

DESIGN FOR A HAIR-HOLDER.

SPECIFICATION forming part of Design No. 24,963, dated December 10, 1895.

Application filed October 26, 1895. Serial No. 567,034. Term of patent 3½ years.

To all whom it may concern:

Be it known that I, ANNIE BERLIN, a citizen of the United States, residing at Buffalo, in the county of Erie and State of New York, have invented and produced a new and original Design for a Hair-Holder, of which the following is a specification.

This design relates to the configuration of a holder for retaining a lady's hair in place, and the same is illustrated in the accompanying drawing, which forms part of this specification, and represents a perspective view of a hair-holder embodying my design.

The leading feature of the design consists of a central ring and radial loops projecting from the ring.

A is the ring, and B are the loops radiating from the outer edge of the ring and spaced unequally around the same. The loops are flared at their outer ends and are curved rearwardly from about their middle to their flared ends, while their inner portions are straight and arranged in the plane of the ring. 20

What I claim is—

The design for a hair holder, substantially 25 as herein shown and described.

ANNIE BERLIN.
